UNITED STATES PATENT OFFICE.

JOHN J. FLANNERY, OF EAST CAMBRIDGE, AND MICHAEL B. PLUNKETT,
OF ROXBURY, MASSACHUSETTS.

COMBINATION FOLDING CHAIR.

SPECIFICATION forming part of Letters Patent No. 728,454, dated May 19, 1903.

Application filed March 13, 1902. Serial No. 97,977. (No model.)

To all whom it may concern:

Be it known that we, JOHN J. FLANNERY, residing at East Cambridge, in the county of Middlesex, and MICHAEL B. PLUNKETT, residing at Roxbury, in the county of Suffolk, State of Massachusetts, citizens of the United States, have invented new and useful Improvements in Combination Folding Chairs, of which the following is a specification.

10 The object of this invention is to provide a chair having the following features: First, a back adjustable at different angles with the seat; second, an adjustable foot-rest; third, means by which said chair may be used as a 15 spring-rocker; fourth, means by which said chair may be used as a swivel-chair, and, fifth, a construction whereby the different parts of the chair may be disconnected and the chair collapsed and packed in a small 20 space in order that the same may be stored or shipped with ease.

The object of this invention is, again, to provide a chair which shall be of cheap and strong construction, in which the different 25 changes hereinbefore set forth may be made with speed and ease.

The invention consists in a chair so constructed that the back may be adjustable at different angles with relation to the seat, that 30 the seat may rock upon the frame, and that said frame may be so constructed as to swivel upon the base of the chair, the whole structure so arranged and constructed as to be readily collapsible.

35 The invention, again, consists in the improved means by which the extent of rocking motion of the seat may be adjustably controlled; and, again, the invention consists in the improved means of attaching a spring 40 between the swivel-frame and seat, so that said spring may be subjected to compression and tension.

The invention, again, consists in the construction whereby the different parts may be 45 readily detached from each other and the chair collapsed and packed in small space for the purpose specified.

The invention finally consists in the combination and arrangement of parts set forth 50 in the following specification and particularly pointed out in the claims thereof.

Referring to the drawings, Figure 1 is a perspective view of our improved collapsible combination-chair, showing the same in position for use. Fig. 2 is a perspective view 55 of the same collapsed and ready to be stored or shipped. Fig. 3 is a vertical transverse section taken on the line 3 3 3 of Fig. 1. Fig. 4 is a vertical longitudinal section taken on line 4 4 of Fig. 3, the dotted lines indicating the chair back and arms in a second position and the foot-rest drawn forward from beneath the seat. Fig. 5 is a detail plan of the seat, illustrating the foot-rest drawn forward from beneath said seat. Fig. 6 is a detail section taken on line 6 6, Fig. 5, illustrating the construction of the sliding frame upon which the foot-rest is supported, the foot-rest being shown in dotted lines in connection therewith in its forward position. 70 Fig. 7 is an enlarged section illustrating the construction and means of attachment of the spring to the seat and to the swivel-frame, taken on line 4 4 of Fig. 3. Fig. 8 is an enlarged section illustrating the connection of 75 the rocking frames to the swivel-frame, taken on line 7 7 of Fig. 4.

In the drawings, 10 is a base-plate provided with legs 11 11, fastened securely thereto by bolts 12, which extend through ears 13, projecting downwardly from said base-plate. A swivel-plate 14 is connected to the base-plate 10 by a central bolt 15, a ball-bearing 16 being provided to insure the free rotation of the swivel-plate 14 upon said base-plate 10. 85 The swivel-plate 14 has provided at each side thereof an upwardly-extending ear 17, to which rocker-plates 18 18 are pivotally attached by bolts 19. The rocker-plates 18 are forked to straddle the ears 17, the bolts 19 being square in cross-section, as at 20, where they pass through one arm of said-fork, and cylindrical throughout the remainder of their length, each bolt being provided with a thumb-nut 21, by which said bolt is fastened to the 95 rocker-plate 18. The square portion 20 of the bolt 19 prevents said bolt from rotating when the thumb-nut 21 is screwed thereon in attaching the rocker-plate 18 to the swivel-plate 14. The rocker-plates 18 are provided 100 with flanges 22, to which the frame of the chair-seat 23 is fastened by screws 24.

A back 25 is pivotally connected at 26 to the chair-seat 23. The arms 27 are pivoted at 28 to the back 25 and at 29 to a link front-support 30, which in turn is pivoted at 31 to 5 the seat of the chair. Between the seat 23 and the swivel-plate 14, at the rear central portion thereof, is provided a spiral spring 32, the upper end of said spiral spring bearing against a cylindrical plate 33, provided with 10 downwardly-projecting ears 34, said ears being bent inwardly and curved around the wire forming the spring 32, thus fastening said spring to said plate 33. The lower end of the spiral spring 32 rests against an arm 35, said 15 arm projecting rearwardly and downwardly from the swivel-plate 14, and being provided with ears 36, which extend upwardly and inwardly to partially encircle the lowermost coil of wire in the spring 32, and thus fasten 20 said wire to said swivel-plate.

In order to limit the extent to which the seat can tip forwardly in its rocking motion, a rod 37 is provided, the upper end of which is pivotally attached to a pin 38, fast to ears 25 39 upon a bolt 40, which extends upwardly through the plate 33 and through the frame of the chair-seat 23 and is fastened thereto by a nut 41. Said bolt also fastens the plate 33 to the frame of the chair-seat 23. The 30 rod 37 projects downwardly through a hole 42 in the arm 35 and is screw-threaded at the lower end thereof to receive a thumb-nut 43 and a rubber collar 44, interposed between said thumb-nut and the under surface of the 35 arm 35.

The seat 23 has two vertical guide-pieces 45 extending longitudinally and fast to the under side thereof. The foot-rest 46 is provided with pins 47, which extend into slots 40 48, running lengthwise of the side pieces 49 of the slide-frame 50. The slide-frame 50 is provided with pins 51, extending into slots 52 in the guide-pieces 45. In Figs. 1, 3, and 4 the foot-rest, together with the slide-frame 45 50, is shown pushed back under the seat 23. In Fig. 5 the foot-rest is shown, together with the slide-frame 50, pulled out from under the seat 23, the same being shown in dotted lines in Fig. 4 also pulled out from under the seat 50 23. In pulling the foot-rest out from the position shown in Figs. 1, 3, and 4 to that shown in dotted lines in Fig. 4 and in full lines, Fig. 5, the pins 47 of the foot-rest slide forwardly in the slots 48, formed in the slide-frame 50, 55 and the pins 51 in the slide-frame 50 slide forwardly in the slots 52, formed in the guide-pieces 45, thus forming a long foot-rest when drawn outwardly, the same shutting up compactly beneath the seat when pushed there- 60 under, as shown.

The back 25, arms 27, and front-supporting links 30 are locked in position at any desired angle by an arm 53, pivoted at 54 to said links 30, the lower end of said arms 53 65 engaging racks 55, fast to the side pieces of the chair-seat 23. Each of the arms 53 is provided with a handle 56, by means of

which they may be lifted out of contact with the racks 55 and set at any desired tooth upon said racks. 70

It will be seen that by the construction hereinbefore described the chair-seat may be rocked upon the pivotal bolts 19. Said chair-seat may swivel by rotating the swivel-plate 14 upon the base-plate 10. The chair back 75 and arms may be adjusted at any angle by changing the location of the arms 53 upon the racks 55, and the foot-rest 46 may be drawn outwardly, as shown in dotted lines, Fig. 4, 80 and in full lines, Fig. 5, or the same may be pushed back beneath the seat of the chair when not in use. It will further be seen that by adjusting the thumb-nut 43 the extent to which the chair may be rocked will be limited through the rod 37, to which said adjusting-nut is fastened. When the chair rocks forwardly, the rubber collar 44 forms a cushion. As the chair is rocked it will be seen that it is under the control of the spiral spring 32, 90 said spring being under tension when the chair is rocked forwardly and under compression when the chair is rocked rearwardly, and, finally, by reference to Fig. 2 it will be seen that the chair may be collapsed and packed in very small space for shipment or 95 for storage.

The chair is collapsed by removing the bolts 12, which secure the legs 11 to the base-plate 10, and by removing the cushions 57 and tipping the back 25 forwardly until the arms 27 100 and links 30 and back 25 assume substantially a horizontal position. The cushions and legs are then placed upon the back and seat, as shown in Fig. 2. If desired, the swivel-plate 14 may be removed from the rocker-plates 18 by unscrewing the thumb-nuts 21 and removing the bolts 19. The central bolt 15, connecting the swivel-plate 14 and base-plate 10, is also removed by unscrewing the thumb-nut upon the lower end 110 thereof. To disconnect the spring 32 from the plate 33 and from the arm 35 upon the swivel-plate 14, said spring is rotated in the proper direction, so that the ends will screw 115 out of connection with the ears 36 upon the arm 35 and ears 34 upon the plate 33, said spring being returned to its position, as shown in Fig. 7, by screwing the same into connection with the ears 34 upon the plate 33 and the ears 36 upon the arm 35. 120

Having thus described our invention, what we claim, and desire by Letters Patent to secure, is—

1. In a collapsible chair, a base-plate provided with suitable legs, a swivel-frame rotatively attached to the base-plate, said frame being provided with a rearwardly-extending member, a seat pivotally connected to the swivel-frame, a rod pivotally attached to the seat and engaging the member projecting 125 from the swivel-frame, and means to adjust the operative length of the rod. 130

2. In a collapsible chair, a base-plate having suitable legs, a swivel-frame rotatably

attached to the base-plate, said frame being formed with a rearwardly-extending member, a seat centrally pivoted to the swivel-frame, a rod connecting the seat and said projecting member, a nut to adjust the operative length of the rod, and a cushion intermediate the nut and said projecting swivel-frame member.

5 3. In a collapsible chair, a base-plate having suitable legs, a swivel-frame rotatably attached to the base-plate, an integral member projecting rearwardly from the swivel-frame, a seat centrally pivoted to the swivel-frame, a rod connecting the seat and projecting member, means to adjust the operative 10 length of the rod, a spring encircling the rod and bearing against the seat and projecting member, and means formed integral with said projecting member to engage and secure the 15 spring.

20 4. A collapsible chair comprising a base-plate, legs removably fastened thereto, a swivel-frame rotatably attached to said base-plate, a seat pivotally attached to said rota-

tory swivel-frame, a rod pivotally attached to said seat extending downwardly therefrom and through said swivel-frame, a stop adjustably fastened to said rod beneath said swivel-frame and adapted to engage said swivel-frame and adjust to different distances the extent to which said seat can rock upon 25 its pivot, a spiral spring encircling said rod, one end of said spring bearing against said seat the other end against said swivel-frame, and ears fast to said seat and to said swivel-frame engaging each end of said spring substantially as described for the purpose specified.

In testimony whereof we have hereunto set our hands in presence of two subscribing witnesses.

JOHN J. FLANNERY.
MICHAEL B. PLUNKETT.
